(57) **CLAIM**

The ornamental design for a material handler tower, as shown and described.

DESCRIPTION

FIG. 1 is a perspective view of our new design for a material handler tower;

FIG. 2 is a front view thereof;

FIG. 3 is a rear view thereof;

FIG. 4 is a side view thereof;

FIG. 5 is an opposite side view thereof;

FIG. 6 is a top view thereof;

FIG. 7 is a bottom view thereof;

FIG. 8 is a perspective view thereof shown in condition of use;

FIG. 9 is a perspective view of the second embodiment of our new design for a material handler tower;

FIG. 10 is a front view thereof;

FIG. 11 is a rear view thereof;

FIG. 12 is a side view thereof;

FIG. 13 is an opposite side view thereof;

FIG. 14 is a top view thereof;

FIG. 15 is a bottom view thereof;

FIG. 16 is a perspective view thereof shown in condition of use;

FIG. 17 is a perspective view of the third embodiment of our new design for a material handler tower;

FIG. 18 is a front view thereof;

FIG. 19 is a rear view thereof;

FIG. 20 is a side view thereof;

FIG. 21 is an opposite side view thereof;

FIG. 22 is a top view thereof;

FIG. 23 is a bottom view thereof;

FIG. 24 is a perspective view thereof shown in condition of use;

FIG. 25 is a perspective view of the fourth embodiment of our new design for a material handler tower;

FIG. 26 is a front view thereof;

FIG. 27 is a rear view thereof;

FIG. 28 is a side view thereof;

FIG. 29 is an opposite side view thereof;

FIG. 30 is a top view thereof;

FIG. 31 is a bottom view thereof;

(Continued)

FIG. 32 is a perspective view thereof shown in condition of use;
 FIG. 33 is a perspective view of the fifth embodiment of our new design for a material handler tower;
 FIG. 34 is a front view thereof;
 FIG. 35 is a rear view thereof;
 FIG. 36 is a side view thereof;
 FIG. 37 is an opposite side view thereof;
 FIG. 38 is a top view thereof;
 FIG. 39 is a bottom view thereof; and,
 FIG. 40 is a perspective view thereof shown in condition of use.

The broken lines in the Figures show portions of the material handler tower which form no part of the claimed design. The additional broken lines in FIGS. 8, 16, 24, 32 and 40 show environment that is not part of the claimed design.

1 Claim, 40 Drawing Sheets
